No. 806,395.

PATENTED DEC. 5, 1905.

C. T. CLARK.
PORTABLE HEATER.
APPLICATION FILED APR. 27, 1905.

UNITED STATES PATENT OFFICE.

CHARLES T. CLARK, OF CLEVELAND, OHIO, ASSIGNOR OF ONE-THIRD TO
GUSTAVUS A. KARPER, OF CANTON, OHIO, AND ONE-THIRD TO ROBERT
FARREN, OF CLEVELAND, OHIO.

PORTABLE HEATER.

No. 806,395.

Specification of Letters Patent.

Patented Dec. 5, 1905.

Application filed April 27, 1905. Serial No. 257,638.

To all whom it may concern:

Be it known that I, CHARLES T. CLARK, a citizen of the United States, residing at Cleveland, in the county of Cuyahoga and State of Ohio, have invented certain new and useful Improvements in Portable Heaters; and I do hereby declare that the following is a full, clear, and exact description of the same, reference being had to the annexed drawings, making a part of this specification, and to the numerals of reference marked thereon, in which—

Figure 1 is a side elevation showing the different parts of the heater properly connected. Fig. 2 is an enlarged view showing a portion of the burner and heater proper.

The present invention has relation to portable heaters; and it consists in the novel construction hereinafter described, and particularly pointed out in the claim.

Similar numerals of reference indicate corresponding parts in both the figures of the drawings.

In the accompanying drawings, 1 represents a radiator of any general design and construction commonly used in hot-water heating systems and is preferably mounted upon the platform 2, which platform is mounted upon casters 3 for the purpose of convenience in moving the heater proper from place to place, as desired, or connecting the heater in different rooms or places where gas-pipes, such as 4, may be located, by which arrangement a portable water-heater is produced.

Near the bottom or lower end of the radiator 1 is located the water-pipe 5, which water-pipe is connected to the T 6, from which T extends the coiled heating-pipe 7, which coiled heating-pipe is located directly above the burner 8 and within the casing 9, which casing is formed of a length to correspond with the length of the coiled heating-pipe 7. For the purpose of utilizing substantially the entire amount of heat produced by the burner 8 the convolutions of the coiled heating-pipe 45 are formed of a diameter corresponding substantially with the diameter of the casing 9, as illustrated in the drawings. From the coiled heating-pipe 7 extends the pipe 10, which pipe is connected to the elbow 11, and to the elbow 11 is connected the pipe 12, which pipe communicates with the top or upper end of the radiator 1, as illustrated in Fig. 1. To the bottom or lower end of the T 6 is connect-

ed the tank-pipe 13 by means of the elbow 14 or its equivalent. To the top or upper end of the tank-pipe 13 is attached the tank 15, which tank may be of any desired size and is for the purpose of filling the radiator 1 and at the same time containing a sufficient amount of water to normally cover the steam-vent pipe 16, which vent-pipe leads into the bottom or lower end of the tank 15 from the opposite upper end of the radiator 1, to which the pipe 5 is attached, or, in other words, the water-pipe 5 is attached to the lower portion of the radiator 1 and the vent-pipe is attached to the upper end and upon the opposite edge from that to which the water-pipe is attached. In use the radiator and tank are supplied with water and a sufficient amount of water to have the normal water-line above the outlet of the vent-pipe 16.

In use the burner 8 when supplied with fuel will heat the coil-pipe 7 and of course the water contained therein, and the water will circulate by reason of the heat in the usual manner, or, in other words, the heated water will move upward and the cold water downward and a continuous circulation be brought about. For the purpose of providing for the escape of steam the tank 15 is open at its top; but the vent-pipe is covered with water, so that any escape of steam will be mingled with the water in the tank and of course be condensed, so that there is no visible exhaust of steam at any time.

It will be understood that by my peculiar arrangement I am enabled to provide a water-heater that can be moved from place to place and one that contains a heating device independent of any boiler or outside heating system, thereby providing a cheap water-heating system and one well adapted for use in dwelling-houses and other places without the necessity of installing an expensive and complicated water-heating system. The burner 8 and its connections form no particular part of the present invention, so far as detailed construction is concerned, but should be so formed that it can be easily attached to the radiator proper and is movable with the radiator. The gas-pipe 17 may be formed of flexible material, thereby providing means for changing the position of the radiator or heater proper with reference to the gas-pipe 4. By providing the tank-pipe 13 and extending it down-

ward and connecting the same to the T 6 wa-
ter will pass from the tank into the bottom or
lower end of the radiator, and as the radiator
fills with water it will find its level in heat-
ing-pipe 7, thereby continually keeping the
coil-pipe 7 full of water. It will be under-
stood that the pipe 12 is an inlet-pipe and the
pipe 5 an outlet-pipe, so far as the circulation
of water is brought about by heat; but of
course when the radiator is being supplied
with water the pipes 5 and 12 are both inlet-
pipes.

Having fully described my invention, what
I claim as new, and desire to secure by Letters
15 Patent, is—

In a heater of the class described, a radiator,
inlet and outlet water-pipes connected there-

to, a heating-pipe located intermediate the in-
let and outlet pipes, and a burner adapted to
heat the heating-pipe, a tank located above the
burner and a feed-pipe for said tank extended
below the burner and communicating with the
lower portion of the radiator, and a vent-pipe
leading from the upper portion of the radiator
and communicating with the tank at a point 25
below the normal water-line of the tank, sub-
stantially as and for the purpose specified.

In testimony that I claim the above I have
hereunto subscribed my name in the presence
of two witnesses.

CHARLES T. CLARK.

Witnesses:
